(57) **CLAIM**

The ornamental design for a display screen with user interface, as shown and described.

DESCRIPTION

FIG. 1 is a front view of a display screen with user interface showing the new design; and,

FIG. 2 is an enlarged partial view of FIG. 1.

The broken line showing of the two magnifying glass-shaped images, the remainder of the user interface and the display screen is for environmental purposes only and forms no part of the claimed design.
